[57] CLAIM

The ornamental design for a pair of shoe soles or similar article, as shown and described.

DESCRIPTION

FIG. 1 is a perspective view of the right component of a pair of shoe soles or similar article showing my new design, the left shoe sole being a mirror image and being omitted for convenience of illustration;

FIG. 2 is a top plan view thereof;

FIG. 3 is a bottom plan view;

FIG. 4 is a left side elevational view thereof;

FIG. 5 is a right side elevational view thereof;

FIG. 6 is a front elevational view thereof; and,

FIG. 7 is a rear elevational view thereof.

The broken lines showing a shoe upper throughout the views serve to illustrate the environment, and are not part of the claimed design. Additionally, the textures characterized by the groupings of small rectangular shapes; and groupings of dots and small curved line segments are understood to repeat across the surfaces of the shapes containing the textures.
